DESIGN FOR AN EVENING GOWN ENSEMBLE

Germaine Monteil, New York, N. Y.

Application November 4, 1940, Serial No. 96,277

Term of patent 3½ years

To all whom it may concern:

Be it known that I, Germaine Monteil, a citizen of the United States, residing at 955 Fifth Avenue, New York city, in the county of New York and State of New York, have invented a new, original, and ornamental Design for an Evening Gown Ensemble, of which the following is a specification, reference being had to the accompanying drawing, forming part thereof.

I claim:

The ornamental design for an evening gown ensemble, substantially as shown.

GERMAINE MONTEIL.
